DESIGN FOR A HANDKERCHIEF

Adolf Finaly, New York, N. Y., assignor to Alfred Kohlberg, Inc., a corporation of New York

Application February 7, 1935, Serial No. 55,297

Term of patent 7 years

To all whom it may concern:

Be it known that I, Adolf Finaly, a citizen of the United States, residing at New York, county of New York, State of New York, have invented a new, original, and ornamental Design for a Handkerchief, of which the following is a specification, reference being had to the accompanying drawings, forming a part thereof.

The drawings show a plan view of a handkerchief having my design formed therein.

I claim:

The ornamental design for a handkerchief, as shown.

In witness whereof, I affix my signature,

ADOLF FINALY.
